ABSTRACT OF THE DISCLOSURE

A tendon prosthesis for use in tendon surgery particularly where there is complete or extensive loss of the tendon, structurally including an elongated member made from a flexible, chemically inert material having at least one flap at each end adapted to overlap the tendon and means for firmly anchoring the prosthesis to the tendon providing a strong, functional anastomotic union.

SUMMARY OF THE INVENTION

This invention relates to improvements in tendon surgery and more particularly, to improvements in a tendon prosthesis for use in tendon repair and reconstruction especially where there is complete or extensive loss of the tendon.

Accordingly, a primary object of this invention is an improved tendon prosthesis which provides a strong, functional anastomotic union between the prosthesis and tendon.

A further object is a full-function tendon prosthesis which is able to withstand full weight bearing capacity without separation or deformity.

Another object is a tendon prosthesis which is chemically inert and demonstrates a very low order of reactivity eliminating any incapacitating foreign body reactions.

Another object is a versatile tendon prosthesis which is adaptable to a variety of clinical situations including instances of soft tissue avulsion, severe infection, electrical burn and surgical resection.

Another object is an improved tendon prosthesis which substantially eliminates adhesions and allows the patient to regain full range of motion including the ability for full active extension and flexion.

Another object is a tendon prosthesis which may be easily positioned and one positioned moves through the surrounding tissue with little resistance.

Another object is an improved method of constructing a strong and durable tendon prosthesis which necessitates no further surgical operations.

Other objects and advantages will be apparent from the ensuing specification and drawing for this invention.

BRIEF DESCRIPTION OF THE DRAWINGS

The invention is illustrated by the accompanying drawings wherein:

FIG. 1 is a perspective view of the tendon prosthesis;

FIG. 2 is a plan view of the prosthesis with portions removed for clarity;

FIG. 3 is an enlarged perspective view of one end of the prosthesis showing a method of suture attachment, and

FIG. 4 is a perspective view showing the tendon prosthesis in final position.

DESCRIPTION OF THE PREFERRED EMBODIMENTS

Referring to the drawing in more detail it will be seen that this invention basically includes an elongated member 12 made from a substantially inert material having flaps

2

14 at each end adapted to overlap a repaired or reconstructed tendon 16. In addition a suture material 18 is incorporated within the elongated member 12 and each flap 14 has a mesh or netting 20 on its inner surface as shown in FIGS. 1 and 2.

5 As shown in the figures the tendon prosthesis 10 is preferably an elongated member 12, however, it may be fabricated to any desired size and shape. The elongated member 12 is preferably fabricated from a sheeting material and may be reinforced as shown in FIG. 2 by a Dacron mesh 15 or similar material. The reinforcing increases the strength of the elongated member and prevents stretching during suture attachment. In addition, the elongated member 12 may be modified by the doctor 10 sculpturing it to any desired size and shape at the time of surgery.

15 It is extremely important that the material used to form the elongated member 12 be substantially inert to prevent foreign body reactions. In addition the material must 20 be compatible with the physiological processes of the human body and preferably has nonwetting surfaces which minimize sticking or encrustation. Further the material should contain the quality of nonadherence to tissue and is preferably resistant to adsorption, hardening and degeneration. A flexible silicone elastomer manufactured by Dow Corning sold under the trademark "Silastic" has been found to substantially meet the above mentioned qualifications. In addition other medical-grade silicone elastomers, or material similar to "Silastic" or equivalents 25 thereof have been found as satisfactory material for the elongated member 12.

30 As best shown in FIGS. 1 and 2 a suture material 18 may be fabricated within the elongated member 12 by bonding two or more layers of sheeting material around the suture material. The ends of the prosthesis 10 are then spread apart to form a pair of flaps 14 for overlapping the repaired or reconstructed tendon. On the inside surface of each flap 14 there is secured a mesh or netting 20 forming suitable end plates for tendon anastomosis. The flaps 35 14 with the mesh or netting 20 are devised to facilitate rapid and accurate areas of anastomosis with minimal exposure.

35 It is important that the mesh or netting 20 be made from a material or materials that cause fibroblastic infiltration to occur between the severed ends of the tendon 16 and the mesh 20 thereby firmly anchoring the prosthesis 10 with a strong, functional anastomotic union. One such material is polyester, however, similar materials or equivalents thereof have been found as a satisfactory mesh material.

40 FIGS. 3 and 4 show how the suture attachment is performed in more detail. The flaps 14 overlap the tendon 16 with the mesh material resting against the outer surface of the tendon while the suture material 18 may 45 be attached to each end of the tendon as shown in these figures. It should again be noted that the suture material 18 runs the full-length of the prosthesis 10 providing a strong durable means for attaching the prosthesis. The fibroblastic infiltration which occurs between the severed tendon 16 and the mesh 20 of each flap insures a 50 strong, functional anastomotic union.

55 The use, operation and function of this invention are as follows:

60 The results from experiments and clinical use of this invention have been very favorable. The tendon prosthesis 10 allows the patient to regain essentially full range of motion within a short time after cast removal. In addition the prosthesis does not cause restrictive adhesions, infections or extrusions. Further, the tendon prosthesis 65 can withstand full weight bearing capacity with no gross deformity including the ability for full active extension and flexion.

On reexploration of experimental uses of this invention each of the tendon prostheses were in good position and completely covered with a layered fibroblastic membrane. This delicate membrane was vascularized and substantially resembled normal synovial tissue. In fact the appearance of the entire tendon prosthesis 10 is very similar to a normal tendon.

Functionally, the tendon prosthesis, and to a lesser degree its fibroblastic membrane, were found to move through the surrounding tissue with very little resistance. When the membrane was dissected, the respected tendon ends were noted to be firmly anchored to the prosthesis by the mesh material of the end flaps 14. In addition the membrane encasing, caused by the material of the elongated member, extended distally and around the normal tendon to reinforce the anastomosis.

It should be emphasized that the tendon prosthesis 10 was designed primarily as a full-function tendon after only one surgical procedure. Further surgical operations such as revision or replacement are not contemplated with this invention. However, it may be noted that if separation of an anastomosis did occur, it could be removed easily and the reactive membrane formed around the prosthesis could be utilized as a sheath for an autologous graft.

I claim:

1. A tendon prosthesis for replacement of the damaged portion of a tendon as a full-function tendon including:
  - a elongated member made from a flexible substantially inert material that is compatible with the physiological processes of the human body;
  - a pair of flaps in opposed relationship at each end of the elongated member, said flaps being integral with the elongated member and having an inside surface for enveloping the severed ends of the tendon and an outside surface designed for movement in the surrounding body tissue;
  - a mesh material secured to the inside surface of each flap adapted to contact only the severed ends of the tendon to form a strong, functional anastomotic union, said mesh material being separated from the surrounding body tissue by the flaps; and
  - suture means running longitudinally the full-length of the prosthesis and extending beyond the end flaps for initially attaching the prosthesis to the tendon.
2. The structure of claim 1 further characterized in that the elongated member including the end flaps is made from a nonwetting, nonreactive material.
3. The structure of claim 1 further characterized in that the elongated member including the end flaps is made from a medical-grade silicone elastomer.

4. The structure of claim 1 further characterized in that the elongated member including the end flaps is reinforced with a mesh material to increase its strength.

5. The structure of claim 1 further characterized in that the mesh material is made from a polyester adapted to cause fibroblastic infiltration therethrough, thereby anchoring the prosthesis to the severed ends of the tendon.

6. In a tendon prosthesis for use in repairing a damaged tendon, the process of making the prosthesis including the steps of:

bonding together a plurality of layers of medical-grade silicone elastomer sheeting over a suture material extending length-wise therein;

fabricating an elongated member from the medical-grade silicone elastomer sheeting;

separating the distal ends of the prosthesis to a desired length to form end flaps having an inner surface and an outer surface, said inner surface being adapted to overlap the severed tendon;

placing a polyester mesh on the inner surface of each end flap for contacting only the severed ends of the tendon and thereby being separated from the surrounding body tissue by the end flap; and

bonding the polyester mesh to the inner surface of each end flap.
